The ornamental design for a pitched roof service platform, as shown and described.

DESCRIPTION

FIG. 1 is a front elevation view of a pitched roof service platform, showing our new design;

FIG. 2 is a rear elevation view thereof;

FIG. 3 is a top plan view thereof;

FIG. 4 is a right elevation view thereof; and,

FIG. 5 is a left elevation view thereof.

The broken lines illustrate portions of a pitched roof environment which form no part of the claimed design.

The pitched roof service platform is shown with a symbolic break in its length. The appearance of any portion of the pitched roof service platform between the break lines forms no part of the claimed design.
